(No Model.)

H. ROBERTS.

APPARATUS FOR COATING METALS WITH METAL.

No. 268,127.

Patented Nov. 28, 1882.

UNITED STATES PATENT OFFICE.

HENRY ROBERTS, OF JOHNSTOWN, PENNSYLVANIA.

APPARATUS FOR COATING METALS WITH METAL.

SPECIFICATION forming part of Letters Patent No. 268,127, dated November 28, 1882.

Application filed January 25, 1881. (No model.)

To all whom it may concern:

Be it known that I, HENRY ROBERTS, a citizen of the United States, residing at Johnstown, Cambria county, in the State of Pennsylvania, have invented certain new and useful Improvements in Apparatus for Coating Metals with Metal in a Melted State, of which the following is a specification.

The invention relates to the wiping to remove the surplus of melted metal.

I will describe the invention as applied to the treatment of common round wires, which I will assume are drawn down from rolled rods of Bessemer steel; but it may be understood that any metal capable of being coated with zinc or analogous metal may be substituted, and that the wires may be flat, round, or of various other sections, and that they may be known as "wires," or by the various other technical names, as "hoop-iron," "bale-ties," or the like.

I have discovered and practically wrought out peculiarly-efficient means for wiping off the surplus metal by the application of the material known as "mineral wool," "slag-wool," or "silicate-cotton." It is a silky fibrous matter, produced by the treatment of cinder from a blast-furnace by blowing it with a current of steam at high pressure. "Slag-wool," as I will hereafter term it, is highly elastic and smooth, is not destroyed by the heat, and has but a slight affinity for or property of adhesion to the melted metal, and is sufficiently frictionless, elastic, and mobile in its nature to allow of being worked by rollers, so as to be moved in the manner which I will describe, and which is made the subject of a separate application for patent. I lead the wires in an inclined direction upward from the bath of melted metal through a mass of this wiping material. The wiping being effected by active contact with this material immediately on the emergence of the wires from the melted bath, I can reduce the consumption of zinc to a minimum. The wires emerge from the wiping-box thinly and uniformly coated, and present a remarkably perfect surface. The preparation of the wires to receive the melted zinc and the treatment in the bath of zinc may be of the ordinary and long-approved character.

The accompanying drawings form a part of

this specification, and represent what I consider the best means of carrying out the invention.

Figure 1 is a vertical section through the apparatus. The remaining figures represent details detached. Fig. 2 is a central vertical section of my improved wiping-box. Fig. 3 is a plan view of a portion of the same, showing the ends of the agitating-rolls, their operating- gear, and the partition space at the side.

Similar letters of reference indicate like parts in all the figures.

I will describe the wiping of only one wire; but it will be understood that the apparatus may treat a series of wires traversed side by side at a proper distance apart.

A is a reel supplying the wire to be coated. m is the wire; B, an acid-tank; C, a quantity of acid and gravel therein; D, rollers therein; E, a roller on the delivering end of the acid-tank; G, a furnace; F, a tube in the upper part thereof; H, a roller on the edge of the metal bath; I, the metal bath heated by a furnace below and around it, (not represented;) and J J' are provisions for holding the wire under the surface of the bath of melted metal. K is a box containing the wiping material, and k is the wiping material. L and P are rollers immersed in the wiping material, and l are projections thereon.

On emerging from the metal bath I the wires are led up through slots in the bottom of a partially-overhanging box, K, which contains a liberal supply of the slag-wool k, which serves as the wiping material, and the upper surface of which should be kept damp with water or tungstate of soda. The wires are led in an inclined direction through this box, and emerge with just a sufficient coating of zinc ready to be wound in coils for sale or use.

An agitation and circulating movement of the wiping material are attained by rollers L, mounted in the wiping-box, and turned by gearing in the direction indicated by the arrows. The surfaces of the several rolls are armed with projections l, which engage with a just sufficient quantity of the slag-wool and drag it along in the direction opposite to the movement of the wires m. The slag-wool is in its nature a good non-conductor. Its temperature is soon raised by the working, so that it ap-

proximates closely to that of the melted zinc, except that the upper stratum is kept wet and relatively cool by sprinkling with water, either ordinary fresh water or preferably a solution of 5 tungstate of soda. The melted zinc removed by the particles of slag-wool, moved actively toward the receiving side of the box, is deposited in that edge of the box and dropped through the openings there provided into the 10 tank. The affinity or adhesion of the melted metal to the earthy wool is very slight.

The lower part, K², of the side of the wiping-box nearest to the tank of melted metal is made in a separate piece from the rest, and can 15 be removed on taking out the screws k', which are inserted through lugs in the upper portion, K', of the side. This facilitates the removal of the finely-broken wiping material, which tends to accumulate there.

20 The mineral wool is superior as a wiping material to anything before known to me. Its fibrous character and its moderate gravity enable it to be moved by the rollers in a very different manner from the sand and charcoal 25 which have, until recently, been universally employed. Its disposition to curl and its greater frictional properties cause it to be worked by any agitating means and to act upon the melted metal brought up by the wires very differently 30 from the straight earthy fiber known as "asbestus," which has been much used within a few years past. The several fibers of mineral wool, sometimes termed "slag-wool," employed in my invention, engage with each other and cling 35 with a force which makes the material peculiarly adapted both for effectually wiping the wires and for being worked and moved by rollers or other agitating means.

Modifications may be made in the forms and

proportions of the details. I have worked successfully with the wiping-box only about two (2) feet wide, so as to give a wiping traverse of only two (2) feet; but this may be varied. I believe that little gain would result from an increase of the wiping traverse in treating wire 45 of small size, because wires of small size become rapidly cooled. For very large wires a wider wiping-box would be expedient.

There is a tendency of the slag-wool to become worn, abraded, or broken, so as to accumulate a fine dust in the bottom. When this has become too fine I replace it with fresh. No particular difficulty is experienced if considerable of the broken earthy matter falls upon the melted zinc.

55 The mechanism shown, by which to present the wiping material with continually-changing surfaces, and with a motion in the opposite direction to that of the wires, is made the subject of a separate application for patent; so also certain peculiarities of the acid bath and drying-furnace form the subject of a separate application for patent.

55 I claim as my invention—

In apparatus for coating wire, a wiper, 65 through which the several wires pass to remove the surplus metal, composed of artificial mineral fiber, known as "slag-wool," combined with means for moving and working the said material, substantially as herein specified.

70 In testimony whereof I have hereunto set my hand, at New York city, New York, this 19th day of January, 1880, in the presence of two subscribing witnesses.

HENRY ROBERTS.
